UNITED STATES PATENT OFFICE.

HATTIE HOFFMAN, OF NEW YORK, N. Y.

BOBBED-HAIR HOLDER AND ROLL.

Application filed December 19, 1922. Serial No. 607,790.

To all whom it may concern:

Be it known that I, HATTIE HOFFMAN, a citizen of the United States, residing in New York, in the county of New York and State 5 of New York, have invented certain new and useful Improvements in Bobbed-Hair Holders and Rolls, of which the following is a specification.

This invention relates to a toilet article, 0 and more particularly to a hair roll or form.

The principal object of the invention is to provide a device of this kind for securely holding and forming the short or bobbed 5 ends of hair against the head of the wearer to give the appearance of a solid roll or puff of the wearer's hair.

Another object of the invention is to provide a hair form so constructed as to exert a tensional grip or hold on the hair regardless of the amount of hair, and which will not easily get out of position.

Other objects of the invention will appear as the description proceeds; and while herein details of the invention are described, the invention is not limited to these, since many and various changes may be made without departing from the scope of the invention as claimed.

In the accompanying drawing, showing 0 by way of example one of many possible embodiments of the invention, Fig. 1 is a perspective of the roll or puff from the rear.

Fig. 2 is an outside or back plan elevation of the clasp in closed position.

Fig. 3 is a top plan view of the clasp.

Fig. 4 is a sectional side elevation of my device, on line 4—4 of Fig. 2.

Fig. 5 is an outside or back plan elevation of the clasp in disengaged position.

Fig. 6 is an end view of the hook end of the clasp.

By referring to the drawings it will be seen that my device comprises a form or rat 10, Fig. 4, and also shown in dotted lines in Figs. 2 and 3, which may be made of hair, cloth, wire, or any suitable material, and of any desired form or size to suit the wearer. As this form is to be used to roll the ends of bobbed hair on, it is obvious that the diameter of the form or rat will depend largely upon the length of the hair to be rolled. Where the hair is very short the form must be small in diameter in order that the ends of the hair may be concealed. This form may also be made lengthwise straight or

curved to fit the particular part of the head to which it is to be applied, as the entire dressing of the head comprises a plurality of my forms.

A rat holder in the form of a clasp, comprises a head conformable support formed of a single piece of wire bent to provide two parallel curved members 15, having at one end eyes 16 and at their other ends oppositely positioned hooks 18 facing each other and at right angles to said eyes 16. The hook connecting portion of said single wire is bent outwardly and then inwardly continuing the curve of said members 15, to form a convenient elastic band attaching 70 point 20.

A hair clamping and form-engaging member, made of a single wire, is bent to provide two parallel curved clamping members 22, disposed parallel to each other and to said members 15, each portion 22 however being slightly back of and outside of members 15. The portion of clamping member wire connecting members 22 is bent at right angle to members 22 and passes through eyes 16, thereby pivotally engaging with members 15, and is bent again between eyes 16 outwardly and then inwardly to form another attaching point 25, and to keep members 15 spread in proper position. The free ends 80 28 of members 22 are engageable in the hooks 18.

When it is desired to use my device to roll up short bobbed hair to give the appearance of a puff or roll of the wearer's own 90 hair, the clamping members 22, free, are passed through the form or rat 10 lengthwise. The rat and clasp, opened, are then placed between the head and the ends of the wearer's hair with the back part of the form to the wearer's head and the members 22 then hooked into the hooks 18. The form and clasp are then rolled inwardly and upwardly a half-turn when the hair ends will be concealed and the rat and clasp will conform to the head.

An elastic band, or ribbon, or braid of hair, 30, shown in dotted lines in Fig. 4 may then be attached to points 20 and 25 passing on the outside of the hair to hold 105 the roll in position. Pins, of course, may be used in place of the band 30. In most instances, however, when the device is placed in position it will not easily become displaced because of its head-engaging form.

Having thus described my invention, I claim:

1. In combination, a form member to the outside of which the intermediate part of 5 bobbed hair may be disposed; clamping device attached to said member for holding the ends of the bobbed hair upwardly pointing and concealed behind said member and said intermediate portion to form a roll of 10 less than one convolution; and means secured to the form member and extending around the outside of said intermediate portion for holding said form member and roll in place.
  - 15 2. In combination, a hair puff form; a clasp comprising a head conformable portion and a clamping member adapted to engage said puff and said head conformable portion to tensionally hold the short end of 20 bobbed hair therebetween; and means for holding said puff form and bobbed hair against the head of the wearer to give the appearance of a roll of the wearer's own hair.
  - 25 3. In combination, a hair form; a clasp
- cooperating therewith comprising a head-conformable support made of a single piece of wire bent to provide two parallel curved body portions having at one end eyes and at their other ends oppositely positioned hooked portions facing each other, the hook-connecting portion of said wire being bent outwardly and inwardly in the same curve as said parallel body portions; and a clamp made of a single piece of wire bent to provide two parallel curved compressing members having free ends adapted to be engaged in said hooks and disposed outside of said curved body portions, the compressing-members-connecting portion of said clamp wire being bent at right angles thereto and passing through said eyes and bent, between said eyes, outwardly and inwardly in the same curve as said compressing members.

HATTIE HOFFMAN.
